METHOD OF AND MEANS FOR FLOWING
OIL WELLS

Herbert C. Otis, Shreveport, La.

Application July 10, 1933, Serial No. 679,755

25 Claims. (Cl. 103—232)

This invention relates to new and useful improvements in methods of and means for flowing oil wells.

Flowing oil wells by introducing air or gas, under relatively high pressures, into the annular space between the well casing and the tubing has proved to be quite successful under certain conditions, particularly where an uninterrupted flow of large quantities of fluid is obtained. However, when the flow is interrupted, the fluid level in the tubing rises and when flowing is to be resumed, a considerably higher or "kick-off" pressure is required to start the flow than is necessary to maintain it.

Ordinarily, flowing may be maintained at a pressure of approximately from two hundred to three hundred pounds, whereas a kick-off pressure ranges from seven hundred to eight hundred pounds. A considerable investment in air compressing equipment is necessary in order to build up these pressures and it is obvious, because of the lower flowing pressure, that a large part of the investment is idle once the flow is started.

The most efficient flow velocity when employing air or gas under pressure as a flowing or lifting agent, is usually a velocity so low as to border on that at which slippage of the liquid in the tubing is likely to take place, but the possibility of the well "loading up" and ceasing to flow as a result, necessitates a higher pressure in order to maintain flowing. It is the custom to introduce air or gas so rapidly and in such volume as to preclude the danger of loading up, even though such velocity is so high as to result in extremely inefficient flowing.

One of the objects of the invention is to overcome the foregoing difficulties and to provide an improved method and means whereby a more or less constant flow will be maintained without the necessity of the use of kick-off or comparatively high pressures.

A further object of the invention is to provide a method and means whereby the flow may be resumed after the well has been shut down, without the use of kick-off or high pressures, and said flow so regulated that the rate of entry of the fluid flowing into the lower portion of the tubing, or the flowing pressure of the oil and gas mixture or the influent, flowing through the tubing from the well, will be less than the input or working pressure of the air and gas, thus removing the danger of loading up when flowing at low efficient velocities.

Another object of the invention is to provide means for regulating the effective flowing pres-

sures of the lifting or elevating fluids and the influent fluids, whereby a constant and uninterrupted flowing of the influent is approached, and also whereby the evils which have been before recited are more or less overcome.

5

An important object of the invention is to provide a method and means whereby the rate of entry of the influent or oil and gas mixture into the tubing is regulated so that it will be held within the lifting or elevating capacity of the lifting or elevating fluids; and particularly whereby the application of the lifting or elevating energy to the column of fluids in the tubing is constant, while the energy or pressure of the lifting or elevating fluid is also used in opposition to the flowing and submergence pressures to regulate or control the entry of the influent into the tubing.

15

A further object of the invention is to provide means for flowing a well wherein a flow control valve or regulator is normally overbalanced and closed by the submergence pressure of the oil, together with means for subjecting the valve to the pressure of the lifting fluid, whereby the valve is opened when the pressure of the lifting fluid exceeds the combined overbalancing and flowing pressures; but wherein the pressure of the lifting fluid is less than the submergence pressure, but greater than the flowing pressure.

25

Another object of the invention is to provide a control valve or regulator having differential working surfaces exposed to the submergence or bottom hole pressure of the influent, whereby the valve is seated, together with a working surface exposed to the lifting or elevating pressure, whereby a lifting pressure in excess of the differential pressure as applied to the working surface of the valve will unseat said valve, thus permitting the use of a relatively low lifting pressure with a comparatively high submergence pressure.

35

A still further object of the invention is to provide a flow valve arranged to be automatically operated by the variations in the pressures of the fluids, whereby ideal flowing conditions are approximated, and also whereby expensive equipment is eliminated and a simple apparatus is had.

40

An important object of the invention is to provide means whereby the working or elevating pressure is prevented from reaching the producing sands and the harmful effects of such an action avoided.

45

A construction designed to carry out the in- 55

vention will be hereinafter described, together with other features of the invention.

The invention will be more readily understood from a reading of the following specification and by reference to the accompanying drawings, in which an example of the invention is shown, and wherein:

Figure 1 is a vertical sectional view showing an apparatus constructed in accordance with the invention installed in a well casing,

Figure 2 is an enlarged detail sectional view through the valve and nipple,

Figure 3 is an enlarged horizontal cross-sectional view taken on the line 3—3 of Figure 2,

Figure 4 is an enlarged horizontal cross-sectional view taken on the line 4—4 of Figure 2,

Figure 5 is a view similar to Figure 1 showing a modified structure built in accordance with the invention,

Figure 6 is an enlarged sectional detail through the nipple and valve elements,

Figure 7 is an enlarged horizontal cross-sectional view taken on the line 7—7 of Figure 6,

Figure 8 is an enlarged horizontal cross-sectional view taken on the line 8—8 of Figure 6,

Figure 9 is a vertical sectional view of another form of the invention,

Figure 10 is a cross-sectional view taken on the line 10—10 of Figure 9, and

Figure 11 is a cross-sectional view taken on the line 11—11 of Figure 9.

In the drawings the numeral 10 designates a string of tubing or well casing. For the sake of clarity in the explanation the string 10 will be referred to as a casing in order to distinguish it from a smaller string of tubing 12, which is mounted therein; but it is to be understood that the string 10 may be either the well casing or the well tubing, which is usually disposed in the well casing. An upper nipple 13 is connected to the lower end of the tubing 12 by a collar or coupling 15, while the lower end of the nipple is screwed into the upper end of a valve housing 17. The housing is made integral with and has its outer surface substantially flush with a sleeve 17' depending therefrom. The upper end of a lower nipple 30 is screwed into the lower end of the sleeve.

It will be observed that the elements 12, 15, 13, 17, 17' and 30 are each less in diameter than the internal diameter or bore of the casing 10, whereby an upright annular space is maintained between said elements and the casing. This space constitutes a reservoir or flowing channel for the air or gas, which is used as an elevating or flowing agent. The compressed air or gas which is utilized to elevate the influent will be hereinafter referred to as the lifting fluid. In order to seal off the bottom of this channel or reservoir and prevent the influent or oil and gas mixture, or the fluids flowing from the well sands, from entering said channel, the lower nipple 30 is provided with a reduced shank 30' and inverted flexible packing cups 31 are suitably fastened on this shank so as to be expanded by an upward pressure. The nipple has an axial bore 32 which forms an entrant passage for the fluids flowing from the oil and gas sands.

The valve housing 17 has an inclined annular seat 20, which is preferably ground, and which receives the inclined annular shoulder 20' of a valve 18. The valve is provided with radial guide wings 18a, whereby its axial alignment in the housing is maintained. An integral sleeve 25' depends from the bottom of the housing and

terminates short of the nipple 30. This sleeve is disposed concentrically within the sleeve 17' and is considerably less in diameter. By this arrangement, an annular passage or channel 26 is formed between the sleeves. A plug 29 screwed into the bottom of the sleeve 25' closes the same and thereby said sleeve provides a chamber 25. Ports 27 at the upper end of the sleeve 25' provide communication between the passage 26 and the chamber 25. A duct 28 extends through the sleeves and provides communication between the casing and the chamber 25 for the admission of the lifting fluid.

The valve 18 has a reduced stem 22 which extends axially down the chamber 25 and terminates short of the plug 29. Above the duct 28 a collar 21 is made integral with the stem. A flexible packing cup 19, mounted on the stem, receives the collar and is held in position by a washer 23 and jam nuts 24 mounted on the lower end of the stem. The cup 19 has a snug sliding fit in the chamber 25 and prevents bypassing of the fluids entering through the ports 27 and the duct 28. It will be obvious that the influent flowing from the bore 32 by way of the passage 26 through the ports 27 into the chamber 25 will exert a downward pressure against the cup 19 and an upward pressure against the shoulder 20' of the valve; while the lifting fluid flowing through the duct 28 into the lower portion of the chamber 25 will exert an upward pressure against the cup 19.

In the nipple 13 above the valve housing 17, I mount a plurality of removable plugs 14, each having an orifice or port 16 extending therethrough. These ports admit the lifting fluid into the nipple and thus into the column of influent standing in the tubing. By regulating the size of the ports 16, the velocity and the quantity of lifting fluid introduced into the influent column may be controlled and a pre-determined pressure drop in the lifting fluid may be obtained. It is here pointed out that the area of the duct 28 is greater than that of the ports 16, and is preferably of such size as not to cause any appreciable pressure drop in the fluid passing into the chamber 25. By this arrangement, the pressure acting upwardly against the cup 19 and tending to open the valve 18 will, under normal flowing conditions, always be slightly greater than the lifting pressure exerted downwardly on said valve by reason of the fluid introduced through the ports 16.

In describing the operation, it may be stated that the area of the shoulder 20' of the valve, which is exposed to the submergence pressure, is less than the area of the chamber 25. Therefore, the valve would be closed because of the greater pressure exerted on the cup 19. However, in order to induce flowing of the well, the pressure of the lifting fluid entering through the duct 28 is built up so as to overcome the submergence pressure and lift the cup 19, whereby the valve 18 is opened. When the valve is opened the influent will flow upwardly through the housing 17 and will be picked up by the jets or streams of lifting fluid entering the nipple 13 through the ports 16. The combined submergence and lifting pressures will maintain the flow of the well.

If at any time during the flowing, the flowing pressure of the fluids passing upwardly above the valve 18 should too closely approach the pressure of the lifting fluid, due to slippage of the fluids in the tubing string 12, or the too

rapid rate of entrance of the influent, the valve 18 will be seated and prevent further entrance of oil, or partially so, until these conditions have been overcome. Where slippage takes place, the 5 downward pressure on the valve will be so great as to close it, and where the entrance is too rapid, the downward pressure on the cup 19 will become so great as to close the valve. The column of oil standing in the tubing will exert a 10 downward pressure or weight on the inlet valve. This weight will be applied, particularly where there is slippage of the oil. Whenever the weight of the column of oil overcomes the flowing pressure of the oil passing the inlet valve, the weight 15 of said column will close the valve.

When the valve has been closed by slippage or an increased downward pressure thereon, it will remain closed until the excess pressure above has been overcome, by reason of the lifting fluid 20 entering the column of influent through the ports 16 and reducing the weight of such column. When this occurs, the lifting fluid entering through the duct 28 will act against the cup 19 and open the valve. It will be obvious that the 25 amount of influent which may pass the valve 18 is always commensurate with the amount of energy or lifting force, in the form of air or gas, which is introduced through the ports 16. It is 30 obvious that the flow will be governed by the relative proportions and pressures. The tubing can not load up at any time, since the flowing pressure of the influent above the valve 18 will always be less than the lifting pressure of the fluid introduced thereinto.

Flow can be cut off or terminated when desired, either by cutting off the supply of the lifting fluid or by closing the valve controlling the discharge of oil and gas from the tubing. When the flow is stopped by cutting off the supply of 40 lifting fluid, the lifting pressure which is effective through the duct 28 and against the underside of the cup 19, will drop rapidly so that the pressure differential of the submergence pressure acting in conjunction with the flowing 45 pressure will seat the valve 18. It is here pointed out that the valve 18 is of a type which will act comparatively slowly so that the opening and closing will not be sudden, but rather gradual. The wings 18a have a snug sliding fit in the 50 housing 17 and tend to retard the action of the valve. They also prevent whirling of said valve.

If the flow is terminated by closing the tubing at its discharge end, the input pressure of the lifting fluid will still be effective. This fluid entering through the ports 16 will build up pressure in the column of fluid in the tubing and this pressure being exerted downwardly as well as upwardly, will force the valve 18 to its seat. In both instances the valve will remain closed until lifting fluid is again admitted to the casing or the discharge valve of the tubing is opened.

Where the flow has been stopped by cutting off the supply of lifting fluid it will be necessary to build up the pressure exerted against the under- 65 side of the cup 19 sufficiently to unseat the valve 18. The pressure differential in the chamber 25 need not be large. The relative areas of the shoulder 20' and the cup 19 may be such that a lifting pressure of five or ten pounds will overcome the differential and unseat the valve; while the submergence pressure under such conditions may be much higher, as for instance seventy-five or one hundred pounds. However, in order to unseat the valve, the applied lifting pressure 70 must not only overcome the pressure differential

in the chamber 25, but must also lift the valve against the weight of the fluid trapped thereabove. However, as lifting fluid will be admitted through the ports 16, the weight of the trapped fluid will be lightened, thus assuring opening of 5 the valve at the proper time.

When the flow has been stopped by closing the tubing discharge valve, it will be resumed when said valve is opened, whereby the pressure fluid flowing through the ports 16 into the tubing will 10 lighten the load on the valve 18, whereby the effective pressure under the cup 19 may build up sufficiently to open the valve. It is pointed out that in neither case is it necessary to employ a kickoff or excessive pressure of two hundred 15 or three hundred pounds, and the same working elements which maintain flow are utilized to start flow when the same has been stopped.

It is obvious that the valve 18 acts as a regulator and variations in the pressures will move 20 the valve up and down with relation to its seat 20. By this arrangement the entrance or rate of entry of the influent into the tubing is regulated. Under excessive conditions the valve will be entirely closed, but under merely abnormal conditions it may be only partially closed, thus cutting down the passage of the influent through the seat. Where the diameter of the seat is less than that of the bore 32, said seat will function 25 as a bottom hole choke or flow restriction opening. However, the valve 18 co-acting with the seat acts more as a regulator than it does as a true choke. The elements 15, 13, 17, 17' and 30, being tubular conductors, are considered a part 30 of the tubing; and the term tubing is used herein 35 in such broad sense as to include these tubular conductors.

With the apparatus which has been described, the pressure of the lifting fluid in the space between the casing 10 and the tubing 12 is always 40 less than the submergence or bottom hole pressure which acts upwardly against the shoulder 20' and downwardly against the cup 19 in the chamber 25. It is possible under some conditions that the flowing pressure above the valve 18 45 may become greater than the submergence pressure, whereby the valve 18 would remain open and a downward pressure would be exerted against the oil sands which would be detrimental. It is desirable to so proportion and operate the 50 elements that the valve 18 will close before the flow pressure above said valve equals the pressure of the lifting fluid discharged into the tubing through the ports 16. For preventing downward or back pressure reaching the oil sands, I provide 55 a drop valve 33, as is shown in Figures 5, 6 and 8. This valve has guide wings 34 and is mounted in the upper end of the nipple 30. It is ground to fit a seat 35 at the upper end of the bore 32. It is obvious that the upper surface of the valve 33, 60 which is exposed to the downward pressure, is greater than the area which is exposed to the submergence pressure in the bore 32. Therefore, the valve will open and close according to whichever pressure dominates.

As has been before stated, the ports 16 are of such size as to cause a pre-determined pressure drop in the streams of air or gas introduced therethrough into the influent flowing upwardly in the tubing. While the pressure of these streams 70 cannot equal that of the lifting fluid outside of the tubing and within the casing 10, it will, in ordinary operation, rise to within a few pounds of the outside pressure. However, should the valve 18 close and fluid continue to discharge 75

- from the upper end of the tubing, the flowing pressure in the tubing would rapidly drop. As before stated, should the combined lifting pressure and flowing pressure above the valve 33 be 5 come greater than the submergence pressure of the influent, then said valve will be seated. If the upper effective pressure area of the valve 33 is twice that of its lower effective pressure area, then the valve will remain closed and no more 10 fluid can enter the tubing until enough fluid already in the tubing has been discharged from the upper end to cause the pressure above the valve 33 to drop to one-half of that beneath it. It is obvious that this or a similar arrangement 15 will give a margin of safety, whereby the valve 33 will remain closed until a dominating submergence pressure is assured.

In Figures 5 and 6, I have shown an additional cup 36 mounted on the stem 22 and spaced from the cup 19 by a washer 37. The cup 36 is inverted with relation to the cup 19 and is supported on a collar 23', which is held in place by the nuts 24. The purpose of this additional cup is merely to guard against a possible by-passing 25 of the fluids in the chamber 25 and is not essential to the invention.

In Figures 5, 6 and 7, I have shown plugs 14' instead of the plugs 14 provided with counterbores 40 extending from the ports 16' and opening 30 into the tubing. Ball valves 38 are retained in the counterbores by pins 39. These balls form checks and seat against the inner ends of the ports 16' so as to prevent a dominating fluid pressure in the tubing from escaping into the 35 casing 10, particularly where the lifting fluid supply has been cut off.

In Figures 9, 10 and 11, I have shown another form wherein the tubing 12 becomes the conductor for the lifting fluid and the casing or 40 tubing 10 becomes the conductor for the influent. A nipple 45 having an axial bore 46 is disposed in the casing and packed off by inverted cups 47 mounted on the nipple in the usual way. The 45 nipple has a reduced screw-threaded pin 48 at its upper end, which is screwed into the lower end of a bell housing 49. The housing has a reduced neck 50 at its upper end, which is connected with the tubing 12 by a collar 51.

The pin 48 of the nipple has a reduced bore 50 52 provided with an inclined valve seat 53 at its lower end for receiving a tapered valve 54. The valve is provided with radial guide wings 55 having a sliding fit in the bore 52. It is pointed out that the effective pressure area of the valve 54 55 below its seat, is greater than its effective pressure area above its seat, so that the submergence pressure may dominate and close the valve upwardly against its seat. The bell housing has a cross partition 56 provided with ports 57. Between this partition and the pin 48 a pressure chamber 58 is formed in said housing. The housing has outlets or ports 59 just above the pin 48. The valve 54 has a stem 60 extending upwardly from its wings 55 and passing freely through a center aperture 61 in the partition. Lock nuts 62 on the upper end of the stem engage the partition and limit the downward or opening movement of the valve.

A flexible cup 63 is fastened on the stem and 70 supported on a washer 64 resting on the wings 55. The lifting fluid under pressure flows downwardly from the tubing 12 into the nipple 49 and through the ports 57 into the chamber 58, whereby it exerts a downward pressure on the 75 cup 63. The pressure of the column of fluid in

the casing 10 is exerted against the underside of the cup through the ports 59 when the valve 54 is closed. When said valve is opened the flowing pressure is exerted against the underside of the cup. Ports or inlets 65 are provided in the housing above the partition 56 so as to discharge streams of lifting fluid under pressure into the space between the tubing and the casing for the purpose of elevating the influent.

In describing the operation, it is pointed out 10 that the admission of the influent is cut off by closing the valve 54. The area of the cup 63 is considerably greater than the bottom effective area of the valve 54, and therefore the lifting fluid pressure which will open the valve 54 will 15 be considerably less than the submergence pressure. In this, as well as in the other forms, it is essential to maintain a lifting energy or capacity which is greater than the load to be lifted. The underside of the cup 63 offers a greater pressure 20 area than the upper side of the valve 54 and consequently whenever the downward pressure of the influent approaches the slippage stage, a pressure differential is built up in the chamber 58, which tends to lift the cup 63 and close the 25 valve. The valve can only be opened when the lifting pressure exerted downwardly on said cup through the ports 57 becomes greater than the differential in said chamber. It is not believed necessary to discuss the operation any further, 30 as the same principles which have been heretofore explained are present in this form.

While the lifting fluid has been described as air or gas supplied artificially from the surface, 35 it is pointed out that natural gas may be employed. The cups 31 in Figure 1 pack off the casing 10 and by closing the upper end of the casing a storage chamber is formed between the tubing and the casing. It is obvious that if the casing 10 was disposed in a larger casing (not shown) and 40 the gas from below the packers by-passed into the storage space, a natural lifting fluid would be provided. If this fluid did not provide sufficient pressure energy, it could be augmented by artificial pressure from the surface. 45

The description which has been given recites more or less detail of a particular embodiment of the invention, which is set forth as new and useful; however, I desire it understood that the invention is not limited to such exact details of 50 construction, because it is manifest that changes and modifications may be made within the scope of the appended claims, without departing from the spirit of the invention.

What I claim and desire to secure by Letters 55 Patent, is:

1. A well flowing apparatus comprising, a tubing having an influent inlet, means for introducing and reducing the pressure of a lifting fluid into the tubing for lifting the influent flow- 60 up the tubing, means for controlling the admission of the influent, means for operating the controlling means by the lifting fluid, and means for operating the controlling means by the submergence pressure of the influent in opposition 65 to the lifting fluid.

2. A well flowing apparatus comprising, a tubing having an influent inlet and an inlet for admitting a lifting fluid, a valve located between the inlets for controlling the passage of the influent, and means for opening and closing said valve having one side exposed to the pressure of the lifting fluid and its opposite side exposed to the submergence pressure of the influent. 70

3. A well flowing apparatus comprising, a tub- 75

- ing having an influent inlet and a lifting fluid inlet thereabove, and means between the inlets exposed to the opposing pressures of the fluids for operation thereby for controlling the passage 5 of the influent, whereby the flowing pressure of the influent above said means is prevented from equaling the pressure of the lifting fluid flowing through its inlet.
4. A well flowing apparatus comprising, a tubing having an influent inlet and a lifting fluid inlet thereabove for admitting a lifting fluid to the influent flowing upward in the tubing, a valve located between the inlets of the tubing for controlling entry of the influent into the tubing, said valve being overbalanced with respect to the submergence pressure of the influent, and operating means for said valve exposed to the opposite pressures of the lifting fluid and the influent, said valve being controlled in its movement relative to its seat by the pressure differentials of the influent and the lifting fluid, whereby the quantity of influent passing the valve is controlled.
5. A well flowing apparatus comprising, a tubing having an influent inlet and a lifting fluid inlet thereabove for admitting a lifting fluid to the influent flowing upward in the tubing, a valve located between the inlets of the tubing for controlling entry of the influent into the tubing, a chamber below the valve open thereto and having an influent inlet and a lifting fluid inlet, and operating means for the valve having a sliding fit in the chamber between the inlets thereof.
6. A well flowing apparatus comprising, a string of tubing having an influent inlet, a valve controlling the admission of and passage of the influent upwardly in the tubing, means for constantly admitting a lifting fluid under pressure to the tubing above the valve, the valve having opposed unequal working surfaces exposed to the submergence pressure of the influent and a third working surface exposed to the lifting fluid, the working surfaces of the valve being so disposed that the applied pressure differentials of the submergence pressure act to seat the valve to reduce the entry of the influent while the applied pressure of the lifting fluid acts to open the valve and increase the admission of the influent, and means for cutting off the flow of the influent when the valve remains open and the flowing pressure bypasses the same downwardly.
7. A well flowing apparatus comprising, a string of tubing having an influent inlet, means for separating and constantly admitting a lifting fluid under pressure to the tubing above the inlet, and means operated by the pressure differentials of the fluids for cutting off the admission of the influent before the flow pressure equals the input pressure of the lifting fluid.
8. A well flowing apparatus comprising, a string of tubing having an influent inlet, means for constantly introducing a lifting fluid under pressure into the tubing above the influent inlet at a reduced pressure, and means operated by the pressure differentials of the fluids for controlling the admission of the influent to the tubing.
9. A well flowing apparatus comprising, a tubular valve housing having a valve seat, a valve slidable in the housing and engaging the seat thereof, a tubular conductor connected to the upper end of the housing and having inlet ports above the valve, a chamber below the valve seat of the housing connected therewith and having an influent inlet, a piston slidable in the chamber, whereby the influent is received between the valve and said piston, means for admitting a lifting fluid under pressure to the chamber on the opposite side of the piston, and means for packing off the casing below the last named inlet.
10. A well flowing apparatus comprising, a string of tubing having an influent inlet, a valve controlling the admission of and passage of the influent upwardly in the tubing, means for constantly admitting a lifting fluid under pressure to the tubing above the valve, the valve having opposed unequal working surfaces exposed to the submergence pressure of the influent and a third working surface exposed to the lifting fluid, the working surface of the valve being so disposed that the applied pressure differentials of the submergence pressure act to seat the valve to reduce the entry of the influent while the applied pressure of the lifting fluid acts to open the valve and increase the admission of the influent, and means for cutting off the flow of the influent when the valve remains open and the flowing pressure bypasses the same downwardly.
11. A well flowing apparatus comprising, a tubing having an influent inlet, means for introducing and reducing the pressure of a lifting fluid into the tubing for lifting the influent flowing up the tubing, means for controlling the admission of the influent, means for operating the controlling means for the influent, means for operating the controlling means by the submergence pressure of the influent in opposition to the lifting fluid, and means for preventing a back flow of the reduced pressure lifting fluid at its point of inlet.
12. The method of operating oil wells having tubing therein provided with a control valve at its lower end which consists, in admitting an oil and gas influent through said valve located in the lower portion of said tubing, admitting lifting fluid into the tubing above said valve to elevate the influent, reducing the rate of admission of the influent through said valve when the pressure within the tubing above said valve exceeds a pre-determined proportion of the lifting fluid pressure, continuing the introduction of lifting fluid until the pressure within the tubing above said valve has been lowered to a pre-determined proportion of the lifting fluid pressure, and then increasing the rate of influent admission through said valve.
13. The method of operating oil wells having tubing therein provided with a control valve at its lower end which consists, in admitting an oil and gas influent through said valve located in the lower portion of said tubing, admitting a lifting fluid under pressure into the tubing above the valve to elevate the influent, closing said valve to reduce the rate of influent admission when the pressure within the tubing above said valve exceeds a pre-determined lifting fluid pressure, maintaining said valve closed until the ratio of the pressure of the fluid within the tubing above said valve to the lifting fluid pressure has been lowered to a pre-determined extent, then opening said valve to increase the rate of influent admission when said ratio has been lowered to a pre-determined extent.
14. The method of operating oil wells having tubing therein provided with a control valve at its lower end which consists, in controlling the rate of admission of oil and gas into the tubing, closing the control valve in the lower portion of the tubing to cut off the flow of influent, admitting a lifting fluid under pressure into the tubing above the valve to elevate the influent previously entering said tubing, and opening said valve to ad-

mit influent fluids only when the pressure within the tubing above the valve is less than the pressure of the lifting fluid.

15. The method of operating oil wells having tubing therein provided with a control valve at its lower end which consists, in admitting an oil and gas influent into the well tubing through said valve located in the lower portion of said tubing, admitting a lifting fluid into the tubing above the valve to elevate the influent, and regulating the rate of influent admission by said valve so as to maintain a relatively constant ratio between the pressure within the tubing immediately above the valve and the pressure of the lifting fluid.
16. A well flowing apparatus comprising, a tubing for conveying a lifting fluid under pressure down into the well casing, a valve seat at the lower end of the tubing, an influent inlet below the valve seat, the tubing having an outlet above the seat, a valve engaging the under side of the seat, and a pressure operated device in the tubing engaging the valve for opening the same against the submergence pressure below said valve and for closing said valve when the submergence pressure and the flowing pressure exceeds the lifting pressure.

17. The method of operating oil wells having tubing therein and provided with a control valve at the lower portion thereof which consists, in admitting through said valve an oil and gas influent to be elevated into the tubing, introducing a lifting fluid under pressure into the tubing at a point above the entrance of the influent, and regulating the entry of the influent into the tubing through said valve by providing a pressure differential pressure against the combined submergence and differential pressures.

18. The method of operating oil wells having tubing therein provided with a control valve at its lower end which consists, in controlling the rate of admission of oil and gas into the tubing through said valve, closing the control valve in the lower portion of the tubing to cut off the flow of influent, admitting a lifting fluid under pressure into the tubing above the valve to elevate the influent previously entering said tubing, and opening said valve to admit influent fluids only when the pressure within the tubing above the valve is less than the pressure of the lifting fluid.

19. The method of operating oil wells having tubing therein provided with a control valve at its lower end which consists, in admitting an oil influent to the tubing through said valve, admitting a lifting fluid under pressure to the tubing to elevate the oil influent, and controlling through said valve the rate of admission of the oil influent into the tubing by applying the pressure of the lifting fluid directly against the flowing pressure of the oil influent.

20. The method of operating oil wells having tubing therein provided with a control valve at its lower end which consists, in admitting an oil influent to the tubing through said valve, admitting a lifting fluid under pressure to the tubing to elevate the oil influent, controlling through said valve the rate of admission of the oil influent into the tubing by applying the pressure of the lifting fluid directly against the flowing pressure of the oil influent, and cutting off or reducing through said valve the admission of the oil influent when the quantity of the same becomes

nearly equal to the lifting energy of the lifting fluid.

21. The method of operating oil wells having tubing therein provided with a control valve at its lower end which consists, in admitting an oil influent to the tubing through said valve, introducing a lifting fluid under pressure into the flowing influent above its point of entrance into the tubing, cutting off the admission of the influent through said valve after a predetermined amount thereof has been admitted to the tubing, continuing the admission of the lifting fluid until the excess of influent has been discharged from the tubing, and then resuming admission of the influent.

22. The method of operating oil wells having tubing therein provided with a control valve at its lower end which consists, in admitting an oil influent under pressure through said valve to the tubing, reducing the pressure of the lifting fluid and introducing it into the influent for flowing the same upwardly in the tubing, maintaining the flow of the influent into the tubing through said valve by a dominant pressure of the lifting fluid outside of the influent, and controlling the admission of the influent through said valve to the tubing by applying the pressure of the lifting fluid against the flowing pressure of the influent.

23. The method of operating oil wells having tubing therein provided with a control valve at its lower end which consists, in admitting an oil influent under pressure through said valve to the tubing, reducing the pressure of the lifting fluid and introducing it into the influent for flowing the same upwardly in the tubing, maintaining the flow of the influent into the tubing through said valve by a dominant pressure of the lifting fluid outside of the influent, and cutting off the admission of the influent through said valve to the tubing when the flowing pressure of the influent acting downwardly exceeds the submergence pressure of the influent.

24. The method of operating oil wells having tubing therein provided with a control valve at its lower end which consists, in admitting an oil influent under pressure through said valve to the tubing, reducing the pressure of the lifting fluid and introducing it into the influent for flowing the same upwardly in the tubing, maintaining the flow of the influent into the tubing through said valve by a dominant pressure of the lifting fluid outside of the influent, and cutting off the admission of the influent through said valve when the weight of the influent flowing up the tubing exceeds the submergence pressure of the influent.

25. The method of operating oil wells having tubing therein provided with a control valve at its lower end which consists, in admitting through said valve an oil influent to be elevated into the tubing, constantly introducing into the tubing at a point above the entrance of the influent a lifting fluid under pressure, and regulating the rate of entry of the influent through said valve into the tubing by providing a pressure differential in the submergence pressure of the influent and applying the pressure of the lifting fluid against the combined flowing and differential pressures.
